Inventor:

Virgil Homer Abbott

UNITED STATES PATENT OFFICE.

VIRGIL HOMER ABBOTT, OF CARROLLTON, KENTUCKY.

FENCE-POST AND FENCE-STAY.

SPECIFICATION forming part of Letters Patent No. 710,031, dated September 30, 1902.

Application filed March 19, 1902. Serial No. 99,021. (No model.)

To all whom it may concern:

Be it known that I, VIRGIL HOMER ABBOTT, a citizen of the United States of America, residing at Carrollton, in the county of Carroll 5 and State of Kentucky, have invented certain new and useful Improvements in Fence-Posts and Fence-Stays, of which the following in a specification, reference being had therein to the accompanying drawings.

10 My invention relates to certain new and useful improvements in fence-posts, and has for its object a device of this character which shall permit of the dispensation of the well-known objectionable nails, staples, and like 15 fastening means, which must of necessity be driven or otherwise secured in the post for engagement with the strands or lengths of wire. Further, I propose to provide a novel device of this character which will readily 20 enable the several strands of wire to be simultaneously secured to the post and in such a manner that no outward pressure, however great, will cause the strands to be become disengaged from the post, which feature is common 25 to staples, nails, and the like, which readily pull out from the post.

Further objects of the invention reside in the simplicity, economical construction, ease of operation, and efficiency of the construction.

30 With the above and other objects in view the invention further resides in the novel details of construction and combination of parts, to be fully described in the following specification and then set forth in the claims.

35 Referring to the accompanying drawings, forming a part of this application, and wherein like characters of reference indicate similar parts throughout the several views, Figure 1 is an elevation of the invention, illustrating the ground broken away and showing the embedded base; and Fig. 2 is a vertical section through a post or stay.

The base D may be of any form, though I 45 preferably employ one having an open frame, as shown, which base is firmly embedded within the ground. At its upper end or portion the base is apertured and receives in the latter the threaded shank C, carried on the lower 50 end of the post or stay E, a nut F, engaging on said shank C and against the lower face

of the upper end of base D, serving to securely unite the base and the stay or post.

On its outer face the post is flat and smooth and has formed therein horizontally a series 55 of notches G, spaced so as to accommodate the number of strands of wire to be employed on the fence, the notches preferably inclining slightly upward. Intermediate the width of the post and having downwardly-inclined 60 engaging faces are a series of teeth H of less width than the post, the teeth being preferably formed or cast integral with the post and having the lower end of their engaging faces in alinement with the lower wall formed 65 on the post by said notches. Of course it will be understood that the teeth correspond in number to the strands employed.

In order to secure the strands in engagement with the post, I provide face-plate I, recessed, as shown at J, to receive the teeth H, the recesses tapering at their lower ends, as at K, to neatly seat on the inclined engaging face of the teeth. It will be noted that the lower end of the face-plate seats on the upper end 75 of the base D, the face-plate along its length being held in engagement with the post by means of bolts B, passing through both, the tension of which may be readily adjusted through the nuts L on said bolts to draw the 80 face-plate toward the post, as will be readily understood. The upper end of the post also carries a threaded shank M, receiving nut A of a size to extend over and engage the upper end of the face-plate.

85 The above sets forth a practical embodiment of the invention, though it is obvious various constructions may fall within the spirit and scope of the invention as set forth.

Having thus fully described my invention, 90 what I claim as new, and desire to secure by Letters Patent, is—

1. In a device of the type set forth, the combination with a base, of a post secured thereto and having a series of horizontally-disposed notches extending entirely across the outer face of the post, the said outer face of the post being flat and carrying a series of teeth centrally arranged and inclined slightly in an upward direction with their engaging 95 faces in alinement with said notches, a face-plate having a flat inner face and provided 100

with apertures to receive said teeth, said face-plate being clamped to the post and having its inner face contacting with the outer face of the post throughout, with separate means 5 for clamping the face-plate to the post.

2. In a device of the type set forth, the combination with a base, of a post having a flat outer face secured thereto, teeth centrally arranged on said face of the post, with horizontally-disposed notches on the outer face of 10 the post extending entirely thereacross and located at the junction of the teeth and the

post, to receive the strands of wire, and a face-plate having a flat inner face and provided with apertures to receive the teeth, 15 with bolts and nuts for securing the inner face of the face-plate in contact with the outer face of the post throughout, substantially as described.

VIRGIL HOMER ABBOTT.
